RETRACTABLE HOSE-SUPPORTING MEANS
FOR LUBRICATION LIFTSKarl E. Hammer, University City, Mo., assignor
to Gray Company, Inc., Minneapolis, Minn., a
corporation of Minnesota

Application February 4, 1948, Serial No. 6,326

6 Claims. (Cl. 20—0.8)

1

This invention relates to apparatus for servicing motor vehicles. In garages and service stations it is customary to employ rubber or other flexible hoses connected with sources of supply of servicing fluids such as lubricants, compressed air and water, and having valves on their free ends to control the flow of the servicing fluids. Unless these hoses are housed when not in use, they will be constantly in the way of the attendant or service man, who may frequently trip over them, and besides they may be irreparably damaged by contact with sharp tools or edges or by being kinked or driven over, and in many other ways.

It is an object of the present invention to provide apparatus which will house and protect the service hoses when not in use but will automatically lift the valved ends of the hoses when the vehicle is lifted, so that the attendant may select any one of the hoses and use it without dragging it across a floor or pavement. Another object is to provide hose-lifting means for attachment to any make of car lift or hoist, without necessitating any changes in the construction of the latter. Another object is to provide a hanger for supporting the valved ends of hoses, having means for clamping it to the rails or track of the car lift. A further object is to provide a hanger of the character indicated which is adjustable to lifts of different dimensions and makes and to different positions relative to the lifts. Another object is to provide a cover for a hose well casing together with automatic means for moving the cover to one side whenever the car lift starts to rise. Another object is to provide a novel arrangement of rollers at the upper end of a hose well casing to obviate wear and damage to the hoses when pulled out of the casing and to make retrieving of the hoses easier. Another object is to provide novel means for detachably supporting the valved ends of hoses. Another object is to house the supporting means for the valved hose ends within a covered hose well and to provide a member on said supporting means which contacts the cover for the hose well to move the same to one side when the car lift raises the valved hose ends. Other objects will be understood from the following description of the preferred embodiment of the invention shown in the accompanying drawings forming a part of this specification.

In said drawings—

Figure 1 is a perspective view of part of a car lift, shown raised, with the servicing equipment of the invention shown associated therewith.

2

Figure 2 is a fragmentary perspective view of the car lift of Figure 1 shown lowered.

Figure 3 is a top plan view of the hose well with the valved hose ends therein, the cover being thrown open.

Figure 4 is a vertical section on line 4—4 of Figure 3.

Figure 5 is a vertical section on line 5—5 of Figure 4.

Figure 6 is a detail in elevation of the preferred means for supporting the valved ends of the hoses.

Figure 7 is a view similar to Figure 6 but in end elevation.

Figure 8 is a fragmentary sectional elevation of the upper end of the hose well casing and cover, showing the manner in which the valved-end supporting means opens the cover, the latter being indicated in dotted lines in the fully open position.

Figure 9 is a section through one of the clamps for securing the hanger adjustably upon the rail of the car lift.

Referring particularly to the drawings, and first to Figures 1 and 2, a car lift or hoist is shown comprising a hydraulic cylinder C, a plunger P which reciprocates vertically under the influence of hydraulic pressure developed in the cylinder, a cross-head CR secured to the upper end of the plunger and extending horizontally, and a pair of rails R forming a track upon which a motor vehicle may be driven when it is desired to service it. The construction of such a car lift is so well known as to require no further description. If desired, the car lift may be of the pneumatic type. Cylinder C in any case is located below the floor F or pavement and has valve controls (not shown) at any convenient point to permit the operator to elevate and lower the vehicle.

To house and protect the servicing hoses to be described, a hose well casing 10 is supported below the floor F between the rails R and is of sufficient size to receive the full lengths of the hoses, and other parts as will be explained. Within the hose well casing are lubricant hoses 23, 25 and 26 and air hose 24, or if preferred a water hose (not shown) may also be included or substituted for one of the other hoses. Referring to Figure 4, the air hose 24 has a valve 27 on its free end and at its opposite end is secured to a header or fitting 21 supported on a perforated plate 22. A pipe 20 is coupled with fitting 21 and leads through a conduit 19 (concealed below floor F) to a source of compressed air, not shown. As all the other hoses 23, 25, 26 are connected with the same man-

ner to sources of supply of lubricant, etc. it is deemed unnecessary to show the connections for each. A cover 18 is secured in any suitable way to the top of a closed compartment 14 at the upper end of casing 10, and when removed gives access to the headers or fittings in the compartment 14, permitting disconnection of the servicing hoses from their respective supply lines so that the hoses and/or the lines may be blown out or otherwise serviced without spilling any lubricant in that part of the hose well casing in which the hoses are housed.

The casing 10 is preferably a steel box-like structure, rectangular in cross section, with four side walls 11, one of which may be shorter than the others to accommodate the closed compartment 14 whose bottom 22 may rest on the top edge of said shorter wall, as will be understood without illustration. A plurality of flat panels or partitions 13 are arranged vertically within the casing to form a plurality of narrow pockets or compartments, one for each servicing hose. Hence each hose is continuously separated so long as it remains in the hose well, and no hose may become fouled with the others. Automatic retracting or retrieving means is provided for each hose to cause the same to be payed out uniformly and to descend into its compartment or pocket without kinking, coiling or catching on any object; but as such means is no part of this invention it is not shown. A piece of sheet steel, bent into a U, is inserted in the top of the casing, with one wall 15 contiguous to a casing wall 11 and the opposite wall 15 forming also one wall of compartment 14, see Figure 4. The bottom 16 of the U-shaped insert rests on the top edges of partitions 13. Thus with walls 11 the U-shaped insert forms a substantially closed compartment in the top of the hose well casing, in which the valves 50, 51, 52, 27 of the servicing hoses are housed when the hoses are not in use. Strap-reinforced angle bars 12 preferably reinforce the upper end of this compartment and also help to anchor the hose well casing in the foundation or other support. A cover 35, hinged as at 36 to one of the angles 29, bordering the top of the casing, completely closes the compartment in which the valved hose ends are housed. The bottom wall 16 is perforated to permit travel of the hoses therethrough and soft hollow inserts 16^a (Figure 4) may protect the hoses against undue wear as they move up and down through the walls. Hose stops 28, in the form of rubber balls fixed to the hoses just below the valves, may strike the bottom wall 16 to prevent further downward movement of the hoses, and to cushion the shock of a sudden stop, obviating injury to the valves.

To support the valved ends of the hoses so that they may be immediately accessible when the car lift has hoisted a car, a hanger and frame assembly is supported on the car lift so as to rise and descend therewith. The hanger may consist of a tube or pipe 42 which extends horizontally slightly below the level of the rails R and is clamped thereon at its opposite ends by clamps one of which is shown in Figure 9. Each clamp may consist of a rod 40 which is bent at right angles and has a slot 40^b extending longitudinally to receive a key (not shown) in the end of tube 42 so that the rod is slideable in and out of tube 42. Instead of the splined connection shown, rod 40 may be screw threaded within the tube as will be clear without illustration. The other end of rod 40 is a screw threaded as at 40^a and

is passed loosely through a sleeve 38^a integral with a clamp member or jaw 38^b. The upper end of rod 40 is fixed to a second clamp member or jaw 38. A nut 41 threaded on screw threads 43^a bears against the lower end of sleeve 38^a and thus may cause the two jaws of the clamp to approach each other to grip the edge of rail R, as shown. If desired, a stud 39 may be passed through holes drilled in the end of jaw 38^b and in the rail edge, thereby to make the connection semi-permanent. The described construction permits the hanger to be clamped to both rails at any desired point, and also permits longitudinal extension or contraction of the hanger, since the rods 40 may be adjusted in and out of the tube 42. This makes it possible to adapt a standardized construction to several different makes of car lifts.

Secured to and depending from tube 42 is a U-shaped frame 43 on which all the valved hose ends are supported. Preferably valve 50 is supported by a roller 45 on the lower end of frame 43 while valve 51 is similarly supported. A pair of prongs 46 may provide a support for the air hose valve 27. A short cylinder 48, located above the lower end of frame 43, supports valve 52. A fixed arm or finger 47 extends at right angles to the general plane of frame 43 (which is vertical) and provides cover-opening means, co-operating with a lifting-bracket 37 fixed to the underside of cover 35. See Figure 8. In other words, finger 47 is a cam and the lifting-bracket is a cam-follower which is so located that the cover starts to open before the hose valves can come in contact with the cover.

Supported on bearing-blocks 39 are two horizontal rollers 34 on opposite sides of the casting at the top, adjacent to but slightly below the top edges of flanges 29. Two rollers 33, arranged co-axially but spaced apart as at 31, Figure 3, are also arranged on each of the two remaining sides of the casing at the top, being rotatably mounted at one end in flanges 32 and at the other end in the bearing-blocks 39. The gap or spacing 31 is in effect a notch at the top of the casing for receiving tube 42 of the hanger when the hanger has been fully lowered with the car lift. The six rollers 34, 33 provide a protection for the synthetic rubber hoses when they are pulled manually out of the hose well at an angle to the vertical, and also make such pulling (and retrieving) much easier.

From the preceding description the operation of the apparatus will be clear. Assuming that the valved ends of the hoses are always replaced on the hanger after each use, they will always rise with the car lift and hence be readily accessible to the service man while he works on the chassis of the vehicle. However, without hoisting the car, the cover 35 may be opened, exposing the hose compartment as shown in Figure 3, whereupon any one of the hoses may be pulled out manually to service a car. When released, the hose will automatically return to the hose well, and in both outward and return movements it will be guided and protected and eased along by direct rolling contact with one of the rollers 33, 34.

The described apparatus is particularly advantageous in that it does not require a special power lift for the hose ends but employs the car lift, thus effecting an important saving in cost. Another advantage is the fact that the apparatus may be used with any car lift employing two parallel rails for receiving the wheels of a car.

The hose well casing may be placed at the most convenient point between the rails, and wherever it is placed, the hanger can be clamped to the track during installation so as to insure vertical rise of the hoses with the lift without wearing contact with the lined perforations in the bottom wall 16. The apparatus affords perfect protection to the servicing hoses and their valves, it being necessary only to replace the hose ends on the hanger after each use and to close the cover after the serviced car has been driven off the car lift.

Obviously the present invention is not confined to the particular embodiment herein shown and described. Moreover it is not indispensable that all the features of the invention be used conjointly since they may be employed in various combinations and sub-combinations.

Having described a preferred embodiment of the invention, what I claim as new and desire to protect by Letters Patent is:

1. Vehicle-servicing apparatus comprising a power-lift adapted to receive a vehicle and to raise it substantially off the floor, a casing sunk into the floor beneath said power-lift, said casing extending slightly above floor level and having a plurality of horizontal rollers disposed adjacent its uppermost edge and having a pair of horizontally aligned slots in its uppermost edge, a hinged top door mounted upon said casing, an uppermost compartment formed within said casing and having an apertured bottom-wall, a plurality of flexible hoses operatively connected within said casing in extensible side-by-side relationship with the free ends thereof extending into said uppermost compartment through the apertured bottom-wall thereof; stop-means carried by the free ends of said hoses for limiting downward movement thereof relative to said apertured bottom wall, a dispensing nozzle mounted on the free end of each hose and normally disposed in generally upright position within said uppermost compartment, a generally horizontal cross-bar carried by said power-lift and extending generally transversely along the underside thereof, said cross-bar being adapted to enter the slots in said casing when said power-lift is in lowermost position, a generally U-shaped hanger depending from said cross-bar and constructed and arranged to extend within said uppermost compartment when said power-lift is in lowermost position, means removably hooking each nozzle to said hanger to lift each nozzle with the hanger when said power-lift is raised so as to maintain said nozzles in proximity to the vehicle being serviced, and cam-means on said top door and said hanger for flipping said top door to open position when said hanger is moved upward from within said compartment.

2. Vehicle-servicing apparatus including a power-lift for receiving and raising a vehicle substantially off the floor, a compartmented casing sunk in the floor beneath the power-lift, said casing including a lower hose-storage compartment and an upper nozzle-storage compartment, said compartments separated by an apertured wall, a plurality of flexible hoses disposed in the lower compartment and extending through said wall with an end of each hose disposed in the upper compartment, the upper edge of the upper compartment extending above the floor-level and having a cover hingedly secured thereto, a nozzle-hanger secured to the underside of the power-

lift, horizontally aligned vertically-extending slots in the side-wall of the upper compartment between the floor-level and the top of said casing adapted to receive said hanger therein, stop-means secured to each hose adjacent the aforesaid end thereof for limiting the downward movement of said hose, a dispensing nozzle secured to the aforesaid end of each hose and concealable within said upper compartment, and connecting means for securing said nozzles to said hanger and supporting said nozzles within the upper compartment when said hanger is disposed in said slots.

3. Vehicle-servicing apparatus including a power-lift for receiving and raising a vehicle substantially off the floor, a compartmented casing sunk in the floor beneath the power-lift, said casing including a lower hose-storage compartment and an upper nozzle-storage compartment, said compartments separated by an apertured wall, a plurality of flexible hoses disposed in the lower compartment and extending through said wall with an end of each hose disposed in the upper compartment, the upper edge of the upper compartment extending above the floor-level and having a cover hingedly secured thereto, a nozzle-hanger secured to the underside of the power-lift, horizontally aligned vertically-extending slots in the side-wall of the upper compartment between the floor-level and the top of said casing adapted to receive said hanger therein, stop-means secured to each hose adjacent the aforesaid end thereof for limiting the downward movement of said hose, a dispensing nozzle secured to the aforesaid end of each hose and concealable within said upper compartment, and connecting means for securing said nozzles to said hanger and supporting said nozzles within the upper compartment when said hanger is disposed in said slots, said hanger adapted to open said casing by lifting said cover and to elevate said nozzles and hoses when said power-lift is raised whereby to maintain said nozzles in proximity to the vehicle being serviced.

4. Vehicle-servicing apparatus including a power-lift for receiving and raising a vehicle substantially off the floor, a compartmented casing sunk in the floor beneath the power-lift, said casing including a lower hose-storage compartment and an upper nozzle-storage compartment, said compartments separated by an apertured wall, a plurality of flexible hoses disposed in the lower compartment and extending through said wall with an end of each hose disposed in the upper compartment, the upper edge of the upper compartment extending above the floor-level and having a cover hingedly secured thereto, a nozzle-hanger secured to the underside of the power-lift, horizontally aligned vertically-extending slots in the side-wall of the upper compartment between the floor-level and the top of said casing adapted to receive said hanger therein, stop-means secured to each hose adjacent the aforesaid end thereof for limiting the downward movement of said hose, a dispensing nozzle secured to the aforesaid end of each hose and concealable within said upper compartment, and connecting means for securing said nozzles to said hanger and supporting said nozzles within the upper compartment when said hanger is disposed in said slots, cooperating cam-means on said hanger and on said cover for opening said cover when said hanger is raised.

5. Vehicle-servicing apparatus including a

power-lift for receiving and raising a vehicle substantially off the floor, a compartmented casing sunk in the floor beneath the power-lift, said casing including a lower hose-storage compartment and an upper nozzle-storage compartment, said compartments separated by an apertured wall, a plurality of flexible hoses disposed in the lower compartment and extending through said wall with an end of each hose disposed in the upper compartment, the upper edge of the upper compartment extending above the floor-level and having a cover hingedly secured thereto, a nozzle-hanger secured to the underside of the power-lift, horizontally aligned vertically-extending slots in the side-wall of the upper compartment between the floor-level and the top of said casing adapted to receive said hanger therein, stop-means secured to each hose adjacent the aforesaid end thereof for limiting the downward movement of said hose, a dispensing nozzle secured to the aforesaid end of each hose and concealable within said upper compartment, and connecting means for securing said nozzles to said hanger and supporting said nozzles within the upper compartment when said hanger is disposed in said slots, a plurality of hose-guides secured to said casing between the upper edge of the upper compartment and said floor-level for guiding said hoses across the casing-edge.

6. Vehicle-servicing apparatus including a power-lift for receiving and raising a vehicle substantially off the floor, a compartmented casing sunk in the floor beneath the power-lift, said casing including a lower hose-storage compartment and an upper nozzle-storage compart-

ment, said compartments separated by an apertured wall, a plurality of flexible hoses disposed in the lower compartment and extending through said wall with an end of each hose disposed in the upper compartment, the upper edge of the upper compartment extending above the floor-level and having a cover hingedly secured thereto, a nozzle-hanger secured to the underside of the power-lift, horizontally aligned vertically-extending slots in the side-wall of the upper compartment between the floor-level and the top of said casing adapted to receive said hanger therein, stop-means secured to each hose adjacent the aforesaid end thereof for limiting the downward movement of said hose, a dispensing nozzle secured to the aforesaid end of each hose and concealable within said upper compartment, and connecting means for securing said nozzles to said hanger and supporting said nozzles within the upper compartment when said hanger is disposed in said slots, said hanger having a portion thereof disposed beneath the floor-level within said upper compartment when said hanger is disposed in said slots.

KARL E. HAMMER.
